UNITED STATES PATENT OFFICE.

JAMES H. MYRE, OF DETROIT, MICHIGAN.

GAME MECHANISM.

Application filed June 25, 1923. Serial No. 647,585.

My invention relates to a new and useful improvement in a game mechanism in which a swinging seat or the like is released upon the party playing the game scoring in the game and in the present embodiment it is shown applied to a game in which a seat upon which a man or other object is seated is released to swing downwardly so as to unseat the object upon the one playing the game being successful in the game by striking the target which operates the releasing mechanism. My invention relates to the mechanism used for releasing the seat and although I have shown it applied to a seat on which a man is usually seated the mechanism may be employed in various ways.

The object of the invention is the provision of means for directly releasing a score indicator upon the successful operation of the game by the one playing it.

Another object of the invention is the provision of mechanism of this class which will be simple in structure, economical of manufacture and highly efficient in use.

Another object of the invention is the provision of means for facilitating the operation of the releasing mechanism when it has been operated through a successful playing of the game.

Another object of the invention is the provision of means for operating the releasing mechanism directly from the target used in the invention.

Other objects will appear hereinafter.

The invention consists in the combinations and arrangements of parts hereinafter described and claimed.

The invention will be best understood from a reference to the accompanying drawings which form a part of this specification and in which,

Fig. 1 is a perspective view of the invention.

Fig. 2 is a vertical sectional view of the target and its co-operating mechanism.

Fig. 3 is a sectional view taken on substantially line 3-3 of Fig. 2.

Fig. 4 is a sectional view of the releasing mechanism used in the invention.

Fig. 5 is another sectional view of the releasing mechanism used in the invention.

Fig. 6 is a sectional view taken on substantially line 6-6 of Fig. 4, and,

Fig. 7 is a sectional view taken on substantially line 7-7 of Fig. 4.

The invention as shown in the drawings is used as a game in which the target is used for an object of base balls thrown by the players, a man being seated on the supporting member and being released to plunge into a tank of water when the target is struck by a player. The mechanism used in the invention may be utilized for various sorts of games, and the target may be so arranged without disturbing the operating mechanism as to make it available for use with rifles and other different means for striking the target. The seat may be substituted with a scoring board or the like.

In its preferred form, as shown in the drawings, the invention comprises a supporting member 12, which may be constructed for use as a ladder. Hingedly mounted on this supporting member is a seat 13, having a supporting arm, which is arcuate in form, extending from the under surface thereof, adjacent the front edge, downwardly and rearwardly therefrom. The arm 14 is struck on a circle of the same diameter as is described by the front edge of the seat, although by mounting this arm in front of the front edge of the seat the circumference on which it is struck would be diminished. The arm 14 is provided with a notch 15 adjacent the free end thereof, which, when the seat is in operative position, engages a slidable rod 18, slidably mounted in a box 16 which is mounted on the supporting member 12, and on the top of which is mounted a U-shaped guide 17 in which the arm 14 is adapted to engage. Projected through the box 16 are bolts 19 and 19' which project through a shaft 20 upon which is mounted a roller 21 adapted to engage the rod 18. Positioned below the roller 21 is a guide for the rod 18, said guide 22 being mounted on the box 16 in any suitable manner.

Projected through the box 16 are bolts 23 and 23' which extend through a shaft 24 upon which is loosely mounted a roller 25 adapted to engage the rod 18. Positioned upon the bolts 23 and 23' in an embracing relation are spiral springs 26 and 26' which serve to retain the roller in engagement with the rod 18 adjacent the lower end thereof. The lower end of the rod 18 has an inwardly projecting shoe 27 which is adapted for engagement with an electric latch 18 such as is conventionally used on electric door latches, the springs serving

to force the shoe into engagement with the latch. Positioned on the box 16 below the latch is an abutment 29, formed from angle iron which will limit the downward thrust 5 of the rod 18 when released from engagement with the latch.

A base 30 is provided on which is mounted an upwardly projecting plank 31 mounted upon which is padding 32 held in position by a leather covering 33. Secured to the plank 31, at the ends thereof are upright supporting members 34 and 34'. Braces 35 and 35' serve to support the member 31, said braces being attached to the supporting members 34 and 34'. Bolts are projected through the supporting members 34 and 34' and through a box 36 so as to retain said box in position on the member 31, the box being of such size as to permit its entry between the members 34 and 34'. The padding and leather covering and plank 31 are each provided with a registering opening 37 formed therein so that an article thrown therethrough may pass 20 into the box 36. Rotatably mounted on the side walls of the box, at the interior thereof, in suitable bearings 38' positioned in the side walls of the box, is a shaft 38 to which is fixedly attached a stop member 39 having 25 the forward side thereof formed from some yieldable material and the rear side thereof formed from metal plate 40. Mounted within the box 36, adjacent the rear thereof, is a wedge shaped block 41 covered by sheet metal 42. Contact members 43 and 43' are mounted on the inside of the box 36 and are suitably connected to a source of electrical energy. The contact member 43' is connected by a wire 47 to a contact 30 point of a knife blade switch 49. Mounted on the shaft 38 and adapted to swing with the member 39 is a metallic blade 45 which, when the shaft is properly rotated, is brought into contact with a stop 44 mounted 35 on the contact 43. This member 45 is connected by a wire 46 to another contact point of the switch 49, so that when the switch is closed and the member 39 moved to swing on the shaft 38 the circuit through the 40 switch would be closed. This switch is connected by a wire 48 to the electric latch 28. When the switch 50 to which the wire 48 leads is closed a closing of the circuit through the switch 49 would cause an operation 45 of the electric latch and would release the rod 18. The specific structure of the electric latch is not shown as it forms of itself no specific part of this invention and may be of any well known type of electrically operated latches.

Pivottally mounted on one of the walls of the box 16 is a rod 51 which is connected intermediate its ends to the rod 18 and at its free end to a spring 52, the opposite end of said spring 52 being attached

in any desired manner to the box 16. Projecting through the upper wall of the box, so as to be accessible from the seat 13, is a wire 53, which is connected to the free end of the rod 51. By means of this wire 70 the rod 51 may be so moved, against the tension of the spring 52, as to bring the shoe 27 into engagement with the upper surface of the latch to lock the same in position. When the latch is released this 75 spring will force the downward movement of the rod 18.

In operation the member 45 will be brought into contact with the member 44 upon a ball striking the member 39 sufficiently hard to cause it to swing inwardly. The housing or box 16 is provided with a door 54 which permits access to the interior of the box and the box 36 is provided with a similar door 55.

It is believed to be clear that the operating mechanism in the box 16 may be coupled to as many targets as desired so that more than one person may be throwing objects at targets for releasing the seat 90 13 at one time. By mounting the box 36 in the manner indicated, it may be very easily and quickly removed from position or mounted thereon by removing the bolts which are projected through the members 95 34 and 34' and the box and disconnecting the wires.

While I have illustrated and described the preferred form of structure I do not wish to limit myself to the precise form 100 of structure shown but desire to avail myself of such variations and modifications as come within the scope of the appended claims.

What I claim is:

1. In a device of the class described, a member adapted for swinging movement; a contact member mounted thereon; a swingable seat; an arcuate supporting member for preventing the swinging of said seat; a slidale member for engaging said supporting member for preventing the swinging of said seat; an electrical circuit; and means for retracting said slidale member for permitting the swinging of said seat upon the closing of said circuit.

2. In a device of the class described; a supporting member having an opening formed adjacent its upper end; a target swingably mounted intermediate its ends and having its lower portion depending across said opening behind the same; said target normally resting in a position inclined toward the vertical and having its lower end inclined toward the lower portion of said opening; a swingable weight; means for preventing the swinging of said weight; electrical means for releasing said preventing means; a contact carried by said target and adapted upon swinging of said 130

target in one direction a predetermined distance, in response to pressure exerted thereon, for closing a circuit to said releasing means, said contact being placed under tension upon the swinging of said target beyond the vertical in one direction.

3. In a device of the class described, a supporting member having an opening formed adjacent its upper end; a target 10 swingably mounted intermediate its ends and having its lower portion depending across said opening behind the same, said target normally resting in a position inclined toward the vertical and having its 15 lower end inclined toward the lower portion of said opening; a swingable weight; means for preventing the swinging of said weight; electrical means for releasing said

preventing means; a contact carried by said target and adapted upon the swinging of 20 said target in one direction a predetermined distance, in response to pressure exerted thereon, for closing a circuit to said releasing means, said contact being placed under tension upon the swinging of said target 25 beyond the vertical in one direction, and an abutment member having an engaging surface inclined to the vertical for engaging said target upon the swinging of the same 30 beyond the vertical in one direction a predetermined distance for limiting the further placement of said contact under strain.

In testimony whereof I have signed the foregoing specification.

JAMES H. MYRE.
